(57) **CLAIM**

The ornamental design for a combined paint brush and holder as shown and described.

DESCRIPTION

FIG. 1 is a right side, top perspective view of the combined paint brush and holder showing my new design;

FIG. 2 is a right side, top perspective exploded view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof; and,

FIG. 8 is a bottom plan view thereof.

The broken lines illustrate structure or features that form no part of the claimed design.
